DRILL COLLAR FOR WELL DRILLING
STRINGS

Jesse C. Wright, Los Angeles, Calif.

Application November 14, 1936, Serial No. 110,819

17 Claims. (Cl. 255—28)

This invention relates to a well drilling tool and relates more particularly to a drill collar for incorporating in a rotary well drilling string. A general object of the invention is to provide a practical heavy weight drill collar embodying means for effecting the easy recovery of the drill collar and the drilling tool connected therewith, in the event the same becomes caught or sanded in the well bore.

10 Another object of this invention is to provide improvements in drill collars of the general character described and claimed in Letters Patent 2,090,822 entitled Drill collar, granted to me August 24, 1937.

15 In the rotary method of deep well drilling it is customary to provide a drill collar in the drilling string above the bit or drilling tool. A drill collar is a relatively heavy rigid member for lending weight and rigidity to the drilling string immediately above the drilling tool. The outside diameter of a typical drill collar and, therefore, the weight of a typical drill collar of a given length has been definitely limited by the necessity of leaving sufficient clearance around the drill collar to allow a wash-over pipe to be passed downwardly over the collar in the event the drilling tool or the drill collar, or both, become sanded or caught in the well bore. Thus, while it has been recognized as desirable to employ a heavy 25 drill collar it has been impractical to increase the weight of a typical drill collar appreciably without materially increasing its length and a drill collar of great length has numerous disadvantages.

30 Another object of this invention is to provide a drill collar of great weight and minimum length that may be employed without danger of becoming permanently mudded or lost in the well.

Another object of this invention is to provide a 35 drill collar of large diameter and, therefore, of great weight, that may be easily freed for removal in the event that the bit or the drill collar, or both, become sanded or caught in the well.

Another object of this invention is to provide a 40 drill collar that is sufficiently large in diameter to operate as an effective bearing or guide to stabilize and guide the drilling tool and the drilling string.

45 Another object of this invention is to provide a drill collar of the character mentioned embodying the usual circulation passage for handling the rotary mud employed during the drilling operation and a separate means for receiving flushing fluid 50 from a wash-over pipe and for discharging the flushing fluid into the well about the drill collar in the event the drill collar becomes sanded or caught in the well. The auxiliary means for handling the flushing fluid in the drill collar of the present 55 invention assures the recovery of the drill collar 60

and the drilling tool in the event that they become sanded in the well bore.

Another object of this invention is to provide a 5 drill collar of the character mentioned in which the flushing fluid employed for freeing the drill collar is discharged adjacent the lower end of the drill collar and may be discharged at points adjacent its upper end in the event the lower portion of the drill collar is so tightly mudded in the bore that the fluid cannot discharge at that point.

10 A further object of this invention is to provide a drill collar of the character mentioned that embodies a novel trap means for preventing accumulations of sand from clogging the auxiliary 15 fluid handling means.

The various objects and features of my invention will be fully understood from the following detailed description of a typical preferred form and application of the invention, throughout 20 which description reference is made to the accompanying drawing, in which:

Fig. 1 is a longitudinal detailed sectional view of the improved drill collar provided by this invention illustrating a portion of the body in side 25 elevation, and Figs. 2, 3 and 4 are enlarged transverse detailed sectional views taken as indicated by lines 2—2, 3—3 and 4—4, respectively, on Fig. 1.

The drill collar provided by this invention includes, generally, a body 10 to be connected in a 30 rotary drilling string S to form a rigid weight element and means 11 associated with the body 10 adapted to receive flushing fluid from a wash-over pipe to discharge such fluid into the well 35 bore about the drill collar in the event that it becomes lost.

The body 10 is an elongate member intended 40 to be connected in the drilling string S above the drilling tool T. In accordance with the invention the body 10 may be an integral member of steel, or the like, resembling, generally, a typical drill collar except that its major portion is much larger in diameter than the major portion of a 45 typical drill collar. Due to this proportioning of the body 10 it may be of great weight without being longer than a typical drill collar. The body 10 is preferably cylindrical and its upper end portion 12 and its lower end portion 13 are reduced in diameter. The reduced end portions 12 50 and 13 provide annular shoulders 14 and 15 at the upper and lower ends, respectively, of the major portion of the body 10. The upper end of the body 10 may be provided with a tapered screw-threaded socket 16 for receiving a pin 17 55 on the lower end of the string S. Means is provided at the lower end of the body 10 for connecting it in the string or for connecting it with a drilling tool. In the particular arrangement illustrated a tapered socket 18 is provided in the 60

lower end of the body 10 to receive a pin 19 on the upper end of the tool T. A central longitudinal fluid passage 20 extends through the body 10 from one end to the other to handle the circulation fluid or rotary mud during the drilling operation. It will be noted that the body 10 just described is a simple structure that is inexpensive.

The means 11 is an important feature of the present invention as it assures the freeing and recovery of the drill collar in the event it becomes sanded in the well bore due to breaking of the drilling string. The means 11 includes or provides one or more longitudinal grooves 21 in the exterior of the major portion of the body 10. The grooves 21 constitute conduits or channels for handling the flushing fluid. In the particular form of the invention illustrated there are three grooves 21 equally spaced about the body 10. The grooves 21 may be of any suitable shape, for example, they may be square or rectangular in cross section, as illustrated. The fluid channels or grooves 21 extend throughout the length of the major portion of the body 10 to have their upper ends open at the shoulder 14 and their lower ends open at the shoulder 15. The means 11 further includes one or more fluid channels or grooves 22 extending longitudinally in the periphery of the body 10. The grooves 22 extend longitudinally in the periphery of the large diameter major portion of the body 10 and may be spaced between the spaced grooves 21 as illustrated. In practice there may be three equally spaced grooves 22. The fluid conducting grooves 22 may be of the same shape and capacity as the grooves 21. In accordance with the invention the grooves 22 extend upwardly from the lower body shoulder 15 and terminate some distance below the upper body shoulder 14. It will be noted that the grooves 21 and 22 may be readily milled or otherwise formed in the body 10.

The auxiliary fluid handling means 11 further includes means for closing the open outer sides of the grooves 21 and 22 and for controlling the discharge of the flushing fluid from the grooves. In the preferred structure illustrated this means includes a sleeve or tube 23 surrounding the major portion of the body 10 to close off the outer sides of the grooves 21 and 22. The tube 23 may be a simple length of pipe or tubing and may terminate at or slightly beyond the shoulders 14 and 15, as illustrated. The tube 23 is preferably rigidly secured to the body 10. In the simple structure illustrated the tube 23 is secured to the body 10 by welding 24. It will be noted that the tube 23 presents a smooth cylindrical outer surface for contacting the side wall of the well bore so that the drill collar may operate as a guide or stabilizer for the drilling string. The tube 23 in extending across or closing the outer sides of the grooves 21 and 22 effectively separates the grooves and prevents the fluid from passing from one groove to the other.

A cup-like cap 25 is secured to the lower end 65 of the tube 23. The cap 25 may be directly welded to the lower end of the tube 23. The cap 25 extends downwardly around the reduced lower portion 13 of the body 10 so that its interior forms a fluid distributing chamber 26 communicating with the lower ends of the grooves 21 and 22. The lower wall of the cup-like cap 25 closely embraces the reduced portion 13 of the body 10. The chamber 26 places the lower ends of the grooves 21 in communication with the lower ends 75 of the grooves 22. The invention provides a plu-

rality of spaced ports 27 in the wall of the cap 25. The ports 27 are preferably provided in the lower wall of the cap 25 and are spaced and pitched so that the jets of fluid discharging from them are effective in washing away the sand about the lower portion of the drill collar and about the tool T. The ports 27 are circumferentially spaced and are inclined downwardly and outwardly and pitched rearwardly relative to the right hand direction of rotation of the drill 10 collar. The ports 27 are relatively small in diameter to discharge jets of fluid at a high velocity to cut away accumulations of sand about the lower portion of the drill collar and about the bit. The tube 23 is perforated or ported to discharge the flushing fluid from the body grooves 22. In practice the tube 23 may have a series of vertically spaced ports 28 in its wall communicating with each channel or groove 22. The ports 28 are adapted to discharge jets of fluid 20 under pressure outwardly into the well bore throughout the major portion of the length of the drill collar.

The auxiliary fluid handling means 11 further embodies a coupling member 29 at the upper end portion of the drill collar to receive or connect with a wash-over pipe (not shown) to conduct the flushing fluid from the pipe to the grooves 21. The coupling member 29 is a tubular member welded or otherwise rigidly secured to the upper end of the tube 23. The member 29 surrounds the reduced upper portion 12 of the body 10 and its interior constitutes a fluid receiving chamber 30 in communication with the channels or grooves 21. The member 29 connected with the tube 23 as just described, in effect constitutes a continuation of the tube and, accordingly, is rigidly secured to the drill collar body 10. The coupling member 29 carries a thread for receiving or mating with a 40 thread on the wash-over pipe. In the preferred structure a pin 31 is provided on the upper end of the coupling member 29 and carries a coarse thread for mating with an internal thread on the lower end of the wash-over pipe. The pin 31 is tapered so that it is readily received in the end socket of the wash-over pipe. The connecting pin 31 of the member 29 surrounds the reduced body portion 12 with substantial clearance leaving an annular fluid passage 32 for carrying the 50 flushing fluid to the receiving chamber 30.

The invention provides a sand trap in the receiving chamber 30 to prevent the grooves 21 and the other channels of the means 11 from becoming sanded up when the circulation is suspended during a shut down or when the drilling string breaks and results in a suspension of the circulation. The sand trap includes a plurality of vertically spaced shelves or flanges 33 extending horizontally across the interior of the receiving chamber 30. The flanges 33 are annular to form continuous barriers across the interior of the chamber 30. In the preferred structure illustrated the flanges 33 are integral parts of the coupling member 29. Ports 34 are 65 provided in the flanges 33. The ports 34 may be in the form of notches in the inner sides or edges of the flanges 33. The ports 34 of one flange 33 are staggered or circumferentially offset relative to the ports 34 of the other flange. When 70 there is an absence of proper circulation in the well sand may settle downwardly through the passage 32 and collect on the upper surfaces of the flanges 33. These accumulations of sand may extend across or bridge the ports 34 to close 75

off the interior of the chamber 30. The sand bridges thus formed across the ports 34 are easily washed away by the flushing fluid when the wash-over pipe (not shown) is connected with the coupling member 29. The sand trap just described thus closes off the upper end of the auxiliary fluid handling system by accumulations of sand that are readily removed or washed away.

10 In operation the drill collar is connected in the drilling string in the usual manner to serve as a rigid weight element immediately above the bit or drilling tool T. During the drilling operation the great weight of the drill collar concentrated immediately above the drilling tool T is directly applied to the drilling tool to steady the same and to feed the tool into the earth formation. The weight of the short heavy drill collar being concentrated immediately above the tool T resists tendencies of the bit to deviate from the vertical and thus guides the bit to drill a straight vertical bore. Further, the drill collar is large in diameter and is received in the well bore with only slight clearance sufficient for the return 20 flow of the circulation fluid so that it forms a bearing or stabilizer in the drilling string. The cylindrical periphery of the tube 23 may contact the wall of the well bore to guide and stabilize the drilling tool T. It is to be understood that 30 the rotary mud or circulation fluid is pumped downwardly through the string S to flow downwardly through the passage 20 and discharge from the tool T in the usual manner during the drilling operation and that fluid is not passed downwardly through the passage 32, the chamber 30 or the grooves 21 during drilling operations. So long as the usual proper circulation is maintained in the well there will be little or no settling of sand or mud in the chamber 30.

40 In the event that the tool T or the drill collar, or both, become caught in the well, or the drilling string S parts above the drill collar, it may be necessary to deliver flushing fluid to the means 11 to clear or wash away accumulations of sand from around the drill collar and the tool. To accomplish this a wash-over pipe (not shown) is passed downwardly over the string S or the remaining portion of the broken string S and a socketed coupling member on the lower end of the wash-over pipe is threaded on the pin 31 of the member 29. The wash-over pipe may conduct water or other suitable fluid under pressure to the passage 32. This flushing fluid delivered to the passage 32 under pressure readily washes away any bridges or accumulations of sand that may be present on the flanges 33 and thus is free to flow downwardly through the receiving chamber 30 and the grooves 21. The flushing fluid passes from the grooves 21 into the distributing chamber 26 and may pass upwardly into the grooves 22. The ports 21 are adapted to discharge this flushing fluid under pressure in jets which erode or wash away accumulations of sand and mud about the lower portion of the drill collar and about the tool T. The discharge of the flushing fluid is appreciably restricted by the small ports 27 in the cap 25 so that fluid under pressure is delivered to the ports 28. The ports 28 discharge jets of flushing fluid at a high velocity to wash away the accumulations of sand about the drill collar. Fluid discharged from the ports 27 of course flows upwardly around the drill collar to groove and wash away mud and sand that may be packed about it. Thus fluid is discharged from the drill collar at

vertically spaced points to effectively remove accumulations of sand and mud that may be packed about the drill collar. If the lower portion of the drill collar is tightly sanded in the well the fluid may discharge from the upper ports 28. The fluid thus discharged from the upper ports 28 may gradually uncover lower ports and thus ultimately clear the sand from about the entire length of the drill collar.

The wash-over pipe threaded to the pin 31 may be employed to turn or move the drill collar to free the same during or following the flushing operation. In some instances it may be possible to rotate the drill collar by means of the wash-over pipe while pumping the flushing fluid under pressure to the drill collar to discharge from the ports 27 and 28. This rotation of the drill collar of course assists in freeing it for removal. When the drill collar has been loosened or freed it may be removed from the well together with the tool T and the lost portion of the string S. The wash-over pipe (not shown) threaded to the pin 31 may be employed to pull or remove the lost parts from the well.

Having described only a typical preferred form and application of my invention I do not wish to be limited or restricted to the specific details herein set forth, but wish to reserve to myself any variations or modifications that may appear to those skilled in the art or fall within the scope of the following claims.

Having described my invention, I claim:

1. A drill collar for use in a drilling string including, a body to be connected in the drilling string and having a passage for conducting the circulation fluid, a fluid duct separate from said passage and vertically spaced openings for discharging fluid from said duct, and means associated with the body for receiving flushing fluid from a wash-over pipe and delivering it to the duct.

2. A drill collar for use in a drilling string including, a body to be connected in the drilling string and having a passage for conducting the circulation fluid, means for conducting flushing fluid longitudinally of the body and discharging into the well at longitudinally spaced points, and means on the body for receiving fluid from a wash-over pipe and delivering it to the first mentioned means.

3. A drill collar for use in a drilling string including, a body to be connected in the drilling string and having a passage for conducting the circulation fluid and having longitudinal fluid channels, one of said fluid channels discharging at the lower portion of the body, another of said fluid channels discharging at a higher point on the body, and means for receiving fluid from a wash-over pipe to supply fluid to said fluid channels.

4. A drill collar for use in a drilling string including, a body to be connected in the drilling string and having a passage for conducting the circulation fluid and having communicating fluid channels discharging into the well throughout a substantial portion of the length of the body, and a coupling member on the body for receiving a coupling part on a wash-over pipe and conducting fluid from the pipe to said channels.

5. A drill collar to be connected in a well drilling string comprising, an elongate body of large diameter having a longitudinal fluid passage for handling the drilling fluid and a longitudinal external groove, means closing the outer side of said groove, the groove discharging at the lower por-

- tion of the body, and a coupling part on the body for connecting with a coupling part on a wash-over pipe and adapted to deliver fluid from the pipe to the groove.
5. A drill collar to be connected in a well drilling string comprising, an elongate body of large diameter having a longitudinal fluid passage for handling the drilling fluid and a longitudinal external groove, means closing the outer side of 10 said groove, means at the lower end of the groove for discharging the fluid therefrom at circumferentially spaced points, and a tubular coupler at the upper end of the body communicating with the groove and adapted to be engaged by a coupler on a wash-over pipe for conducting circulation fluid.
7. A drill collar to be connected in a well drilling string including, an elongate body having a longitudinal passage for the drilling fluid and 20 having a plurality of longitudinal external grooves, means closing the outer sides of the grooves, a part on the body whose interior forms a chamber communicating with the lower ends of the several grooves, and a coupler on the body 25 adapted to be engaged by a coupler on a wash-over pipe and having a chamber receiving fluid therefrom and communicating with certain of the grooves, said means having ports communicating with the other grooves to discharge fluid therefrom.
8. A drill collar to be connected in a well drilling string including, an elongate body having a longitudinal passage for the drilling fluid and having a plurality of longitudinal external 30 grooves, means closing the outer sides of the grooves, a part on the body having a chamber communicating with the lower ends of the several grooves, said part having ports communicating with the chamber and discharging into the well, 40 and a coupler on the body adapted to be engaged by a coupler on a wash-over pipe and having a chamber receiving fluid therefrom and communicating with certain of the grooves, said means having ports communicating with the other 45 grooves to discharge fluid therefrom.
9. A drill collar to be connected in a well drilling string including, an elongate body having a longitudinal passage for the drilling fluid and having a plurality of longitudinal external 50 grooves, a tube surrounding the body and closing the outer sides of said grooves, there being a chamber in the lower end of the tube communicating with the lower ends of said grooves and discharging into the well bore, and a coupling 55 member at the upper end of the tube for connecting with a wash-over pipe for delivering fluid to the grooves.
10. A drill collar to be connected in a well drilling string including, an elongate body having a longitudinal passage for the drilling fluid and having a plurality of longitudinal external 60 grooves, a tube surrounding the body and closing the outer sides of said grooves, there being a chamber in the lower end of the tube communicating with the lower ends of said grooves and discharging into the well bore, a coupling member at the upper end of the tube for connecting with a wash-over pipe for delivering fluid to the 65 grooves, and a sand trap in the coupling member.
- 70 11. A drill collar to be connected in a well drilling string including, an elongate body having a longitudinal passage for the drilling fluid and having a plurality of longitudinal external grooves, a tube fixed to and surrounding the body
- and closing the outer sides of said grooves, there being a chamber in the lower end of the tube communicating with the lower ends of said grooves and discharging into the well bore, and a coupling member at the upper end of the tube for delivering fluid to the grooves.
12. A drill collar to be connected in a well drilling string including, an elongate body having a longitudinal passage for the drilling fluid and having a plurality of longitudinal external 10 grooves, a tube surrounding the body and closing the outer sides of said grooves, a cap on the lower end of the tube having a chamber communicating with the several grooves and having 15 a discharge port, and a tubular coupler on the upper end of the tube communicating with the grooves and having a thread for mating with a thread on a wash-over pipe.
13. A drill collar to be connected in a well 20 drilling string including, an elongate body having a longitudinal passage for the drilling fluid and having a plurality of longitudinal external grooves, a tube surrounding the body and closing the outer sides of said grooves, a cap on the 25 lower end of the tube having a chamber communicating with the several grooves and having a discharge port, and a tubular coupler on the upper end of the tube communicating with the grooves and having a thread for mating with a thread 30 on a wash-over pipe, certain of said grooves being out of communication with the coupler and the tube having discharge ports communicating with said certain grooves and spaced above the said cap.
14. A drill collar to be connected in a well 35 drilling string including, an elongate body having a longitudinal passage for the drilling fluid and having a plurality of longitudinal external grooves, a tube surrounding the body and closing the outer sides of said grooves, a cap on the lower 40 end of the tube having a chamber communicating with the several grooves and having a discharge port, and a tubular coupler on the upper end of the tube communicating with the grooves and having a thread for mating with a thread on a wash-over pipe, the coupler including vertically 45 spaced internal flanges having fluid ports, the ports of one groove being offset from the ports of the other groove.
15. In a rotary well drilling string, a sand trap including, a tubular member, and longitudinally 50 spaced internal flanges in the member, the flanges having fluid ducts, the ducts of one flange being circumferentially offset from the ducts of the other flange.
16. In a rotary well drilling string, a sand trap including, a tubular member, and longitudinally 55 spaced internal flanges in the member, the flanges having notches in their inner edges forming fluid ducts, the notches of one flange being circumferentially offset from the notches of the other flange.
17. In a rotary well drilling string, a sand trap comprising, an inner member, an outer member 60 telescoped over the inner member with clearance to leave a fluid passage, and vertically spaced flanges on one member extending across the passage to the other member, there being fluid openings through the flanges connecting the portions of the passages separated by the flanges, the 65 openings of one flange being out of vertical alignment with the openings in the other flange.
